UNITED STATES PATENT OFFICE.

JOHN M. HOPWOOD, OF PITTSBURGH, PENNSYLVANIA, ASSIGNOR TO THE HAGAN CORPORATION, OF PITTSBURGH, PENNSYLVANIA, A CORPORATION OF PENNSYLVANIA.

ASH-CONVEYER.

1,351,572.

Specification of Letters Patent. Patented Aug. 31, 1920.

Application filed June 11, 1917, Serial No. 174,038. Renewed January 29, 1920. Serial No. 354,872.

To all whom it may concern:

Be it known that I, JOHN M. Hopwood, residing at Pittsburgh, in the county of Allegheny and State of Pennsylvania, a citizen of the United States, have invented or discovered certain new and useful Improvements in Ash-Conveyers, of which improvement the following is a specification.

The invention described herein relates to that class or type of ash conveyers employing jets of steam for shifting the ashes from the points where they are charged into a conduit to a receptacle or place of storage. It is the usual practice when ashes are to be removed from the pits of furnaces, for the workmen to turn on the steam and then to remove the cover from the opening into the conduit in front of the furnace, scrape the ashes thereinto, replace the cover and repeat the operation in front of each furnace. Intermediate these operations the steam is flowing into the conduits, resulting in an unnecessary use of steam.

The object of the present invention is to provide for the cutting off of the steam jets after the ashes have been removed from each of the ash-pits, and to this end this invention consists in means operative by the plug when shifted from the openings into the conduit, for admitting steam to the nozzle or nozzles in the conduit and automatically operating means to shut off the steam when the plug is replaced. The invention is hereinafter more fully described and claimed.

In the accompanying drawings forming a part of this specification, Figure 1 is an elevation of an ash conveying plant embodying my improvement; Fig. 2 is a similar view of a portion of a plant embodying a modification of the controlling devices, and Figs. 3 and 4 are a plan and elevation respectively, illustrating further modifications of the improvement.

In the practice of the invention, the conduit 1 is of the usual or any suitable form and is provided with openings having suitable removable covers or plugs 2 in front of each furnace of the plant; nozzles 3 and 4 are arranged to direct jets of steam into the conduit at suitable points, as for example, into the lower end of the vertical portion 1^a and into the horizontal portion 1^b. These nozzles have their outer ends connected to

the manifold pipe 5 which is connected to 55 the steam supply pipe 6 provided with the controlling valve 7. The operating arm 8 of this valve is connected to the rod 9 of the piston 10 in the cylinder 11. When relieved from the fluid pressure as hereinafter described, the piston is moved up by a spring 12 to so shift the valve 7 as to permit of the flow of steam through the nozzles. A pipe 13 extending from a boiler or other source of fluid pressure, is connected to the upper 60 portion of the cylinder and is provided with a series of controlling valves 14 arranged respectively in convenient proximity to the openings into the conduit. These valves are of the three-way type and when 65 in normal position permit fluid under pressure to flow to the cylinder and hold the piston down, compressing the spring and closing the valve 7. When the valves 14 are turned as hereinafter described, the flow of 70 fluid to the cylinder is checked and the fluid under pressure in the cylinder and the portions of the pipe intermediate the cylinder and the valve which has been shifted, is allowed to escape, thus permitting the 75 spring to act, raising the piston and thereby opening the valve 7.

The valves 14 are held in normal position by springs 15 connected to the valve operating handles 16. To these handles are connected rods 17 which are provided with suitable means permitting of the ready attachment of the plugs or covers 2 thereto, and thereby cause a shifting of the valve 14 and the consequent opening of the valve 7. The 80 springs 15 are made of such a strength relative to weight of the plugs, as to yield when the plugs are connected to the valve handles. It is preferred that the rod and plug should have complementary engaging members so 85 constructed that while permitting of the easy attachment and removal of the plug, no other object of sufficient weight to turn the valves can be attached to the rods 17, thereby rendering it necessary to employ the 90 plugs to open the valves, and as the replacement of the plugs is necessary for the proper operation of the furnaces, and as such replacement of the plugs involves their 95 removal from the rod 17 and the consequent 100 automatic shifting of the valves 14, the cutting off of the steam jets is insured.

As shown in Fig. 2, a solenoid 20 may be

employed in lieu of the fluid pressure motor 11. In such construction the armature or movable plunger of the solenoid is connected to the valve operating rod 9. The circuit of the solenoid is formed in sections adapted to be connected by blocks 21 carried by levers 22 and adapted when free, to move down and close the circuit thereby closing the valve 7. The levers 22 are provided with means similar to those hereinbefore described whereby the plugs or covers 2 may be connected to the levers while the ashes are being scraped into the conduit.

In the construction shown in Figs. 3 and 15 4, the plug or cover 2 is provided with an arm 23 which is secured to a shaft 24 mounted in suitable bearings and to this shaft is secured an arm 25 connected by a rod 17^a to the handle or operating arm of the valve 14. 20 This construction insures the proper shifting of the valves in the pipe 13 and the consequent operation of the motor controlling valve 7. It will be understood that the term "motor" is used generically herein to include mechanism adapted to shift the valve 7 whether to open or closed position or both.

I claim herein as my invention:

1. In an ash conveying apparatus the combination of an open ended conduit having a plurality of spaced openings therein, a plurality of removable plugs for said openings, a nozzle for directing a jet of fluid under pressure into said conduit to establish a current of air therethrough, a valve controlling the flow of fluid to said nozzle, means for opening said valve, a plurality of means shiftable by the said plugs of the respective openings for controlling the valve operating means.

2. In an ash conveying apparatus, the combination of an open ended conduit having a plurality of spaced openings therein, a plurality of removable plugs for said openings, a nozzle for directing a jet of fluid under pressure into said conduit for establishing a current of air therethrough, a valve controlling the flow of fluid to said nozzle, means adapted to return and hold said valve in closed position, and a plurality of means operative by the respective plugs for moving the valve to open position. 45

3. In an ash conveying apparatus the combination of an open ended conduit having a plurality of spaced openings therein, a plurality of removable plugs for said openings, a nozzle for directing a jet of fluid under pressure into said conduit whereby to establish a current of air through the conduit, a valve controlling the flow of fluid through said nozzle, a motor for normally holding said valve in closed position and adapted to be operated to open the valve by any of the plugs. 55

4. In an ash conveying apparatus the combination of an open ended conduit having a plurality of spaced openings therein, a plurality of pivotally mounted plugs for said openings, a nozzle for directing a jet of fluid into the conduit whereby to establish a current of air through the conduit, a valve 70 controlling the flow of fluid under pressure through the nozzle, a motor for shifting said valve and a plurality of mechanisms operative by the respective plugs for controlling the operations of the motor. 75

In testimony whereof I have hereunto set my hand.

JOHN M. HOPWOOD.
